Primary Examiner—Stella Reid[57] **CLAIM**

The ornamental design for a breast wrap, as shown and described.

DESCRIPTION

FIG. 1 is a front prospective view of the breast wrap of the present invention;

FIG. 2 is a left side elevational view of the breast wrap of FIG. 1, the right view being a mirror image thereof;

FIG. 3 is a top plan view of the breast wrap of FIG. 1; and,
FIG. 4 is a front elevational view of the breast wrap of FIG. 1.

The broken lines showing of a woman in FIG. 1 are for illustrative purposes only and form no part of the claimed design.
